United States Patent Office

Des. 232,643
Patented Sept. 3, 1974

232,643

SHIP MODEL WALL PLAQUE

Francis R. Nartowicz, 204 Fort Worth St.,
Hampton, Va. 23369

Filed Oct. 13, 1972, Ser. No. 297,314

Term of patent 14 years

Int. Cl. D11—02

U.S. Cl. D29—23 A

FIG. 1.

FIG. 6.

FIG. 1 is a front elevational view of a ship model wall plaque showing my new design;

FIG. 2 is a top plan view;

FIG. 3 is a left side elevational view;

FIG. 4 is a right side elevational view;

FIG. 5 is a bottom plan view; and

FIG. 6 is an enlarged fragmentary front elevational view.

I claim:

The ornamental design for a ship model wall plaque, as shown.
